Patented Apr. 4, 1922.

FIG. 1.

FIG. 2.

FIG. 3.

FIG. 4.

Fred Squire INVENTOR.

UNITED STATES PATENT OFFICE.

FRED SQUIRE, OF PEABODY, KANSAS.

TORCH.

1,411,589.

Specification of Letters Patent. Patented Apr. 4, 1922.

Application filed September 11, 1920. Serial No. 409,523.

To all whom it may concern:

Be it known that I, FRED SQUIRE, a citizen of the United States, residing at Peabody, in the county of Marion and State 5 of Kansas, have invented certain new and useful Improvements in Torches, of which the following is a specification.

My invention relates to improvements in torches and more particularly to the self-10 generating type.

The primary object of the invention resides in the provision of a device of this character having a relatively large generating chamber affording a maximum heating 15 surface for the passage of the fuel oil, thus producing a strong and powerful flow of gas.

A further object lies in providing a device of this character adapted and constructed to 20 withstand the intense heat to which it is subjected, being durable, and yet inexpensive to manufacture.

Other objects and advantages of the invention will be apparent during the course 25 of the following description.

In the accompanying drawings forming a part of this specification and in which like numerals are employed to designate like parts throughout the same,

30 Figure 1, is a fragmentary side view of my invention;

Figure 2, is a longitudinally sectional view of the same;

35 Figure 3, is a transverse sectional view on lines 3—3 of Figure 2, and

Figure 4, is an end view.

In the drawings, wherein for the purpose of illustration I have shown a preferred embodiment of my invention, the letter A designates generally a generating chamber of 40 tubular configuration having an inlet opening 5 and an outlet opening 6. The chamber comprises inner and outer walls 7 and 8 arranged in spaced relation to each other, as clearly shown in Figure 2. A spiral partition or wall 9 positioned between the walls 7 and 8 extends the entire length of the generating chamber. This partition divides the casing so as to provide a spiral passage 45

50 10 which encircles the generating chamber as many times as may be desired. The terminal of the passage 10 at the inner end of the chamber, is apertured at 11, from which extends a pipe 12. This pipe extends upwardly at 13, and inwardly as at 14, and has

a nozzle 15 attached to its free end which is on a horizontal plane with the center of the chamber. This nozzle is spaced a slight distance from the inlet end 5 of the chamber and is provided with a needle valve 16 which controls and regulates the flow of gas. The opposite end of the passage is likewise apertured through its outer side, as at 17, from which extends the supply pipe 18 positioned along the side of the generating 65 chamber the entire length thereof.

In operation, the fuel oil, preferably kerosene or gasoline, is introduced through the supply pipe being forced through the passage or channel which encircles the generating chamber. The torch is then heated from 125 degrees to 130 degrees Fahrenheit which is sufficient to vaporize the oil within the chamber converting it into gas which passes through the pipe 12 and is ejected 70 through the nozzle 15. The gas upon being ignited will produce a flame, the force of which is regulated by the needle valve. The flame produced by the gas strikes the inner wall of the generating chamber heating it 75 sufficiently to vaporize fuel oil passing around the chamber through the passage or channel. Thus it is seen that once the torch is heated it will afterwards generate its own fuel. Particular attention is called to the 80 position of the supply pipe 18 which extends the entire length of the generating chamber, so that the fuel oil is slightly heated before entering the main vaporizing chamber. The spiral passage in the generating chamber which directs the flow of oil provides a maximum heating surface 85 whereby the oil is thoroughly vaporized before being ejected, thus producing a very 90 powerful flame.

95 It is to be understood that the form of my invention herewith shown and described, is to be taken as a preferred example of the same, and that certain changes in the shape, size, and arrangement of parts may be resorted to without departing from the spirit of the invention or the scope of the subjoined claims.

Having thus fully described my invention, I claim:—

100 1. A torch of the character described comprising a cylindrical tube having spaced walls forming a generating chamber, a helical partition between the walls forming a helical channel, a supply pipe communi- 105 110

cating with one end of said channel, and an outlet pipe connected with the opposite end of said channel.

2. A torch of the character described comprising a cylindrical tube having spaced walls forming a generating chamber, a helical partition between the walls forming a helical channel the length of said tube, a supply pipe extending the length of the tube 5 in contact therewith and communicating with one end of said channel, an outlet pipe 10

connected with the opposite end of said channel, and a jet nozzle covering the outer end of the outlet pipe for regulating the flow of gas.

In testimony whereof, I have affixed my signature in the presence of two witnesses.

15

FRED SQUIRE.
